UNITED STATES PATENT OFFICE.

JOHN H. MACALPINE, OF PITTSBURGH, PENNSYLVANIA, ASSIGNOR TO THE WESTINGHOUSE GEAR & DYNAMOMETER COMPANY, OF EAST PITTSBURGH, PENNSYLVANIA, A CORPORATION OF PENNSYLVANIA.

FLOATING FRAME.

Application filed July 17, 1919. Serial No. 311,670.

To all whom it may concern:

Be it known that I, JOHN H. MACALPINE, a citizen of the United States, and a resident of Pittsburgh, in the county of Allegheny and State of Pennsylvania, have made a new and useful Invention in Floating Frames, of which the following is a specification.

This invention relates to gearing of the floating frame type and particularly to an improved floating frame for such gearing.

Gearing having one or more members mounted in a floating frame or a plurality of floating frames are well known to those skilled in the art, particularly in connection with gearing for transmitting relatively large powers. The purpose of the floating frame is to allow a part of the gearing, for example, a pinion, to have a slight angular motion sufficient to compensate for distortion (due for example to torsional deflection in the pinion or to warping of the gear casting) and to thereby maintain an even distribution of pressure along the teeth of the pinion. Gearing embodying the floating frame principle may be made lighter for a given power than gearing of the ordinary type, in which the various members are mounted in rigid bearings, because the floating frame gearing does not have to be designed to withstand a concentrated load. The floating frame ensures an even distribution of load along the length of the members of the gear set and effectively prevents any accidental concentration of load. The floating frame type of gearing is particularly familiar in marine installations where the power to be transmitted is large and the stresses on the casing tending to cause deflection are severe, due to the bending and twisting of the ship in heavy seas.

An essential feature of the floating frame gearing is the rigidity of the floating frame, that is, the floating frame must be so mounted that it is capable of a certain amount of angular movement, but it must be sufficiently stiff and rigid to move as a whole and without appreciably bending or warping in itself. The floating frame must be sufficiently rigid in itself to prevent sagging at the ends, either horizontally or vertically, due to bearing pressures producing misalignment of the bearings and consequent

bending and straining of the pinion, and poor load distribution on the teeth of the pinion.

Great strength and rigidity of the floating frame is particularly desirable in double reduction gearing where the intermediate gears and pinions are all mounted in a single, relatively long, floating frame. In such gearing it is common practice to mount the initial or high speed pinion in one floating frame and the intermediate gears and pinions in a second and larger floating frame, the pinions of the intermediate member meshing with the rigidly journaled final or slow speed gear member.

The lubrication of gearing for transmitting large powers is important to the successful operation of such gearing and a further object of my invention is to produce a new and improved oiling arrangement for floating frame gearing.

A further object is to produce a floating frame which is more rigid in proportion to its weight than other floating frames now in use and known to me.

These and other objects which will be made apparent throughout the further description of my invention are attained by means of apparatus embodying the features of my invention herein described and illustrated in the drawings accompanying and forming a part hereof.

In the drawings: Fig. 1 is a diagrammatic view of a floating frame embodying the features of my invention.

Fig. 2 is a diagrammatic sectional view of a portion of a double reduction gear set showing the floating frame, illustrated in Fig. 1 in place.

Fig. 3 is a view from the opposite side of half of the floating frame illustrated in Fig. 1.

Fig. 4 is a sectional view along the line 4-4 of Fig. 1.

Fig. 5 is a sectional view along the line 5-5 of Fig. 1.

Fig. 6 is a fragmental sectional view along the line 6-6 of Fig. 1.

Fig. 7 is a diagrammatic sectional view of a modification of the floating frame illustrated in Figs. 1 to 6 inclusive.

In Fig. 1, I have illustrated a floating

frame 5 suitable for housing an intermediate gear member of a double reduction gear set of relatively large size. In Fig. 2, I have shown the floating frame 5 as mounted in place in a double reduction gear set such as is frequently employed in marine installations for transmitting the power of a turbine to a propeller shaft and for transforming the relatively high speed of the turbine 10 to the low speed at which the propeller operates most efficiently. I have indicated the gears and pinions of the set in dotted lines.

As shown, an initial or high speed pinion 6 is mounted in a suitable floating frame 7, 15 illustrated as of the open type, and is adapted to mesh with intermediate gears 8 mounted in the floating frame 5. The intermediate gears 8 are mounted on a shaft 9 which also carries intermediate pinions 20 10, the shaft 9 being journaled in the floating frame 5. It is evident that the intermediate member (comprising the intermediate gears 8, the pinions 10 and the shaft 9) moves as a whole in response to 25 torsional or other deflections of the intermediate gear member or of the casing which encloses and supports the gears. As shown, the intermediate pinions 10 are adapted to mesh with a large or final gear 11 which 30 may be suitably mounted in rigid bearings not shown. A casing 12 encloses the gearing and the floating frames 5 and 7 and is provided with suitable pedestals 13 on which the floating frame 5 is mounted. It 35 will, of course, be understood that the connections between the pedestals and the floating frame are preferably so constructed as to allow the floating frames to have an angular movement about a horizontal axis 40 approximately normal to the pinion axis. As shown, I-beams 13^a are interposed between the floating frames and the pedestals and have sufficient elasticity to permit this 45 motion, while struts 14 extend from the floating frames to the casing 12 and serve to prevent movements of the floating frame about a vertical axis.

As shown in Fig. 1, the floating frame 5 consists largely of a roughly elliptical 50 shaped peripheral rim portion 15 of rectangular or box cross section. I have shown bearings 16 and 17 at opposite ends of the frame in which the opposite ends of the shaft 9 are journaled. The peripheral rim portion 15 is reinforced at its center by means of a cross strut 18 which also serves as a support for a center bearing 19 for the shaft 9.

As shown, the center bearing 19 supports 60 the shaft 9 between the two intermediate gears 8, shown in dotted lines in Fig. 1. The pinions 10 are interposed between the gears 8 and the end bearings 16 and 17 so that one gear and one pinion are supported 65 between each end bearing and the center

bearing. As illustrated, the gears 8 are provided with helical teeth 20, which are oppositely inclined on the two gears in order that the end thrust caused by the inclination of the teeth is counterbalanced. 70 For the same reason the teeth on the two pinions or pinion halves 10 are also oppositely inclined.

As shown, the rim portion 15 is also strengthened by means of webs 21 which extend across the ends of the frame and which serve to support cylindrical casings 22 for the pinions 10. The webs are shown as provided with ribs 23 which add to the stiffness of the webs and therefore to the stiffness of the peripheral frame 15. I have shown holes 24 in the webs 21 for the purpose of reducing the weight, the arrangement of the holes being such that they do not materially affect the strength of the floating frame. It will, of course, be understood that the frame illustrated is split horizontally, in the usual manner, in order that the bearings and intermediate gear member may be easily installed. During 90 the operation of the gears the two halves are rigidly bolted together and the frame may then be considered as a unit structure.

As illustrated in Fig. 5, the pinions 10 are adapted to operate within the cylindrical casings 22, the front part of the casings being open so that the pinions may mesh with the slow speed gears 11. The casings 22 form a part of the stiffening web 21 and are also employed in effecting the lubrication of the pinions, as will be hereinafter described.

The peripheral rim portion 15 is strengthened and stiffened, as shown, by numerous internal ribs 25 which are preferably arranged so as to produce a maximum degree of stiffness in proportion to the amount of material employed. These ribs are arranged to hold the corners of the box section in shape and therefore greatly increase 105 the torsional rigidity of the member. On account of the asymmetry of the structure this torsional rigidity plays an important part in preventing distortion.

As shown, the floatable frame 5 is provided with suitable feet or pedestals 26 which are formed on the center strut and which are adapted to rest on I-beam supports 13^a, as shown in Fig. 2. In this construction the fulcrum point about which the frame illustrated is adapted to swing is located near the center of the beam. In Fig. 1, I have illustrated sockets 27 near each end of the frame for receiving the inner ends of the struts 14 which prevent the floating frame moving about a vertical axis.

The peripheral rim portion 15, as illustrated, is provided with numerous holes 27^a which are employed for core supports while making the castings and which may be sub- 130

sequently plugged up, if desired, in any suitable manner, for example, by means of pipe plugs.

I have shown an oil or lubricant conduit 27^b extending through the upper portion of the floating frame 5 and having, as illustrated, a centrally located inlet port 28, and similar ports 29 and 30 at the opposite ends of the frame. The oil for lubricating the intermediate gear member may be delivered to any or all of these ports. The lubricant is delivered to the three bearings 16, 17 and 19 by vertical passages 31, 32 and 33 leading from the conduit 27^b to annular oil chambers 34, 35 and 36 which surround the middle portion of the bearings. As illustrated, the bearings are provided with suitable holes 37 for conducting oil to the inner periphery of the bearings.

As shown, the annular oil chambers 34 and 36 communicate directly with oil pockets or passage ways 38 which extend along the back of the floating frame adjacent the cylindrical casings 22 of the pinions 10. The casings 22 are provided with holes 39 for delivering the oil from the passage 38 to the pinion 10. Oil pockets 40 are also shown in the upper part of the casings 22 and holes 41 are provided for delivering oil from the pockets to the pinions near the points of contact with the gears 11.

It is desirable to deliver the oil to the bearings 16, 17 and 19 under some pressure, consequently I have provided restricted openings 42 in the passages or pockets 38 through which the oil must flow before it is delivered to the holes 39, thereby serving to maintain or build up pressure of oil for the bearings. Other restricted passageways 43 conduct oil to the pockets 40 from those portions of the pockets 38 which are in direct communication with the annular oil chambers 34 and 36 surrounding the bearings 16 and 17. Because of the restricted or pressure-reducing openings leading to the delivery holes 39 and 41, the pressure of the lubricant on the bearings may be maintained without necessitating the use of an excessively large oil pump.

In marine installations one end of the gearing is usually higher than the other and consequently the oil tends to fall away from the high ends of the pinions. I have shown ribs or dams 44 in the lower part of the casings 22 for the purpose of maintaining a more or less even distribution of oil along the pinions 10 irrespective of whether the gear set is level or not. I have also illustrated a series of teeth 45 on the outer walls of the pockets 40 for maintaining an even distribution of the oil along the pinions in case the holes 41 clog up and the oil overflows over the wall.

In Fig. 7, I have illustrated a modification of the floating frame, referring particularly

to the upper portion of the frame. As illustrated, the lubricant conduit 27^b is enlarged so as to comprise the top portion of the peripheral box frame and consequently so as to have considerable volume. The box frame therefore serves as an emergency reservoir for lubricant and will supply lubricant to the bearings and gearing for a considerable time, in case of accident to the oil pump.

The floating frame illustrated is more rigid than other floating frames of substantially the same weight and is particularly adapted for large power gearing in which weight is an essential consideration. This type of floating frame may be more expensive to construct than the open type, but is so much more rigid in proportion to its weight as to more than justify the somewhat greater expense. Because of its rigidity and light weight it is particularly valuable in marine installations where the working conditions are severe and weight is of considerable importance. The lubrication system employed is such as to ensure thorough lubrication of the bearings and gear teeth at all times irrespective of the positions of the gear set. Furthermore the lubricant conduits are simple in construction and are so arranged that they assist in stiffening the floating frame.

While I have described and illustrated but one embodiment of my invention, it will be apparent to those skilled in the art that various changes, modifications, additions and omissions may be made in the apparatus described and illustrated without departing from the spirit and scope of the invention as set forth by the appended claims.

What I claim is:

1. In a reduction gear of the double-reduction type, a floating frame having a rim portion, an intermediate strut portion, and web portions spaced therefrom to define gear openings, said web portions being provided with pinion-receiving pockets.

2. In a reduction gear of the double-reduction type, a floating frame comprising a hollow rim portion having interior strengthening ribs, an intermediate strut member, and web portions having pinion-receiving pockets, the web portions being spaced apart from the strut to define gear-receiving openings.

3. A floating frame having a peripheral rim portion of box section, bearings at opposite ends of the frame, a lubricant conduit formed in the peripheral rim portion, and passageways for conducting lubricant from the conduit to the bearings.

4. In a floating frame for supporting a gear member, a peripheral rim portion of box section, casing partially enclosing the gear member and forming parts of the floating frame, and means for maintaining a distribution of lubricant within said casings.

- 41
5. In a floating frame for gearing, a peripheral rim portion of box section, a center strut extending across the peripheral frame, lubricant conduits of box section extending to the casings and designed to permit a restricted flow to said casings whereby oil pressure is built up and maintained for said bearings. 45
5. In a floating frame for gearing, a peripheral rim portion of box section, a center strut extending across the peripheral frame, lubricant conduits of box section extending along the back of the floating frame, and webs for connecting said conduits with the peripheral frame whereby said peripheral frame is stiffened and strengthened. 50
6. A floating frame for gearing comprising a hollow peripheral rim portion having interior ribs to resist deflection, bearings carried by the ends of said frame, a center strut for strengthening and stiffening said frame, a bearing carried by said strut, and a longitudinal lubricant conduit carried by the upper portion of said frame and communicating with the bearings. 55
7. A floating frame for gearing comprising a hollow peripheral rim portion having interior ribs to resist deflection, bearings carried by the ends of said frame, a center strut for strengthening and stiffening said frame, a bearing carried by said strut, end webs for strengthening and stiffening said frame having pinion casings, means for supplying lubricant to the bearings, a passageway arranged back of the frame and in communication with the bearings, conduits for conducting lubricant from the passageway to the casings, and means within the casings to assure distribution of lubricant therein. 60
10. A floating frame for gearing comprising a hollow peripheral rim portion having interior ribs to resist deflection, bearings carried by the ends of said frame, a center strut for strengthening and stiffening said frame, a bearing carried by said strut, end webs for strengthening and stiffening said frame having pinion casings, means for supplying lubricant to the bearings, a passageway arranged back of the frame and in communication with the bearings, conduits for conducting lubricant from the passageway to the casings and designed to permit a restricted flow to said casings whereby oil pressure is built up and maintained for said bearings, and spaced circumferential ribs carried by the casings to maintain the distribution of lubricant throughout the length of the pinion. 65
- 20
- 25
- 30
- 35
- 40
8. A floating frame for gearing comprising a hollow peripheral rim portion having interior ribs to resist deflection, bearings carried by the ends of said frame, a center strut for strengthening and stiffening said frame, a bearing carried by said strut, end webs for strengthening and stiffening said frame having pinion casings, means for supplying lubricant to the bearings, a passageway arranged back of the frame and in communication with the bearings, and conduits for conducting lubricant from the passageway
